UNITED STATES PATENT OFFICE

121,387

DESIGN FOR A BUILDING

Lewis C. Franco, New York, N. Y.

Application April 22, 1940, Serial No. 91,836

Term of patent 14 years

To all whom it may concern:

Be it known that I, Lewis C. Franco, a citizen of the United States and a resident of New York, in the county of New York and State of New York, have invented a new, original, and ornamental Design for a Building, of which the following is a specification, reference being had to the accompanying drawing, forming a part thereof.

Figure 1 is a perspective view of a building, showing my new design.

Figure 2 is a top plan view thereof.

Figure 3 is a fragmentary side elevational view. The dominant features of my design reside in the portions shown in full lines.

I claim:

The ornamental design for a building, as shown and described.

LEWIS C. FRANCO.
